UNITED STATES PATENT OFFICE.

CHARLES C. DOTEN, OF PLYMOUTH, MASSACHUSETTS.

TYPE-CASE.

SPECIFICATION forming part of Letters Patent No. 278,782, dated June 5, 1883.

Application filed September 7, 1882. (No model.)

To all whom it may concern:

Be it known that I, CHARLES C. DOTEN, of Plymouth, in the county of Plymouth, and in the State of Massachusetts, printer and publisher, have invented certain new and useful Improvements relating to Type-Cases, of which the following is a specification.

I make the bottom of the type-case of two thicknesses of wire-cloth of different-sized mesh and strength.

The following is a description of what I consider the best means of carrying out the invention.

The accompanying drawing forms a part of this specification, and is a vertical section through a portion of my improved case.

My improved case may be made with the sides and partitions of wood, having the compartments arranged in any ordinary or suitable manner. For the bottom I employ two thicknesses of wire-cloth of the same size and shape as the case, laying one upon the other, the lower one being coarser and stronger than the upper layer. I securely fasten the edges of both all around to the frame of the case by nails or staples, and I secure by the same or different fastenings a cleat or strip of wood applied below, so as to support and protect each edge. At each of the crossing-points of the partitions I introduce a fine wire fastening in the form of a loop, which takes hold of the joint of the partitions, and also takes hold of both thicknesses of the wire-cloth. I thus secure this wire-cloth bottom strongly along the edges, and also at points only a little distance apart along the bottom of the several partitions.

Referring to the drawing, A is the edge, and B B some of the partitions, of the case, made of wood and nicely jointed together, as usual. C C are the two thicknesses of the wire-cloth bottom. D is one of the securing-cleats, and E the fastenings.

G G are the loops of wire embracing the joint or crossing-place of the partition B. They extend down through both thicknesses of the wire-cloth C, and are tightly strained by the ends being twisted together below. The twisted ends are then bent up close to the wire-cloth.

My improved case is always clean. No ap-

preciable quantity of dust can gather on the narrow rounded surfaces of smooth wires.

I prefer that the wire-cloth be of fine wires and open-wove, so as to present considerable spaces for the passage of dust; but care must be taken to avoid the use of wire-cloth having so large meshes as to allow the passage of small type. Brass, as the material for the wires, withstands dampness and acids better than iron or steel; but this point is not absolutely essential.

When type from standing unused becomes particularly dusty I can clean them by simply shaking the case. While the case is in use the usual manipulation keeps the type constantly clean.

I esteem this simple and expeditious method of cleaning the type when dusty one of great importance to compositors.

If bellows are used, I can blow upward from below through the wire-cloth.

As ordinarily used, the openness of the bottom facilitates the passage of the dust downward through it, and the peculiar surface presented of wire-cloth engages with the parts of the type in contact therewith in the act of shaking, so as to thoroughly agitate the mass.

Modifications may be made in many of the details. Parts of the invention may be used without the whole. I can hem or fold over the edge of one or both the layers of wire-cloth to insure against fraying. The edge of the bottom may be left a little within the line of the exterior of the case. The edge of the wire-cloth may be dipped in melted solder or otherwise secured by soldering, the solder being subsequently flattened by rolling or otherwise to reduce the thickness.

I am aware that perforated bottoms for type-cases is not broadly new with me, and such feature, broadly, is not sought to be covered in this application.

What I claim as new is—

1. A type-case having a bottom composed of two thicknesses of woven wire of different mesh and strength, and adapted to serve as and for the purposes set forth. 95

2. A type-case having a bottom composed of two thicknesses of woven wire, the upper finer than the lower, and both secured to the frame in contact, whereby the lower supports the upper, substantially as set forth. 100

3. In a type-case, and in combination with the ordinary partitioned frame, the duplex wire-cloth bottoms C C, of different mesh and arranged as described, and the securing means 5 D, E, and G, all operating as and for the purposes set forth.

In testimony whereof I have hereunto set my

hand, at Plymouth, Massachusetts, this 29th day of June, 1882, in the presence of two subscribing witnesses.

CHARLES C. DOTEN.
